DESIGN FOR A LIGHT-EMITTING DECORATIVE DEVICE

Elmer J. Graf, Roselle Park, N. J.

Application April 18, 1936, Serial No. 62,195

Term of patent 7 years

To all whom it may concern:

Be it known that I, Elmer J. Graf, a citizen of the United States, residing at Roselle Park, in the county of Union, State of New Jersey, have invented a new, original, and ornamental Design for a Light-Emitting Decorative Device, of which the following is a specification, reference being had to the accompanying drawing, forming a part thereof.

Figure 1 is a front elevational view of the light-emitting decorative device, showing my new design.

Figure 2 is a side elevational view; and
Figure 3 is a rear elevational view thereof.
I claim:

The ornamental design for a light-emitting decorative device as shown.

ELMER J. GRAF.
